UNITED STATES PATENT OFFICE.

RICHARD M. PANCOAST, OF CAMDEN, NEW JERSEY.

DESIGN FOR A TOP.

SPECIFICATION forming part of Design No. 34,558, dated May 21, 1901.

Application filed April 11, 1901. Serial No. 55,428. Term of patent 14 years.

To all whom it may concern:

Be it known that I, RICHARD M. PANCOAST, a citizen of the United States, residing at Camden, in the county of Camden and State 5 of New Jersey, have invented and produced a new and original Design for a Top; and I do declare the following to be a full, clear, and exact description of the same, reference being had to the accompanying drawing, forming a part thereof.

The figure is a view in elevation of a top, showing my new design.

As shown by the drawing, the leading or characteristic feature consists in the globular 15 shape of the body and the circumferential slot or groove.

The letter A designates the slot or groove.

B is the visible central part of the axis of the top, which is at right angles to the plane of 20 the slot and defines the depth of the same.

C is the pointed projecting portion of the axis, which extends some distance from the center of the curved surface of the lower portion of the globular body. The external 25 shape of the body portion below the slot is

defined by a curved surface, as from D to E, which extends from the base of the projection of the axis C to the slot or groove. The body portion above the slot has the circumferential curved surface F, as clearly shown, which 30 vanishes into the cylindrical surface adjacent the slot.

The top taken as a whole appears to the eye as a globular body intersected by a deep circumferential slot or groove and having a 35 pointed projection at right angles to the plane of the slot and coinciding with the axial line of the body.

Having described my invention, what I claim as new, and desire to secure by Letters 40 Patent, is—

The design for a top, as herein shown and described.

In testimony whereof I affix my signature in presence of two witnesses.

RICHARD M. PANCOAST.
